UNITED STATES PATENT OFFICE

127,911

DESIGN FOR A COIN HOLDER

Edward R. Norbut, Newark, N. J.

Application September 26, 1940, Serial No. 95,402

Term of patent 7 years

To all whom it may concern:

Be it known that I, Edward R. Norbut, a citizen of the United States, residing at Newark, in the county of Essex and State of New Jersey, have invented a new, original, and ornamental Design for Coin Holders, of which the following is a specification, reference being had to the accompanying drawing, forming part thereof.

Fig. 1 is a perspective view of a coin holder showing my new design.

Fig. 2 is a front elevational view.

Fig. 3 is an end elevational view.

The initials "R. E." appearing on the design are merely for illustrative purposes.

I claim:

The ornamental design for a coin holder, as shown and described.

EDWARD R. NORBUT,
